UNITED STATES PATENT OFFICE.

ANDREW E. MARTINSON, OF NEW YORK, N. Y.

SKI HANDLE.

Application filed December 10, 1927. Serial No. 239,193.

This invention relates to skis, and has for an object to provide an improved form of handle therefor, wherein a support is provided over a considerable distance.

5 A further object of the invention is to provide a ski with a substantially arc-shaped handle in order to provide means whereby the handle may be grasped conveniently by a tall or short person.

10 In the accompanying drawing—

Figure 1 is a perspective view of a ski, disclosing an embodiment of the invention.

15 Figure 2 is an enlarged fragmentary sectional view through Figure 1, approximately on line 2—2.

Figure 3 is a view similar to Figure 2, but showing a modified form of fastening means.

20 Referring to the accompanying drawing by numerals, 1 indicates the body of a ski, which is preferably of the usual shape and may be of any desired length and width. A strap 2 of usual or preferred structure, is secured to body 1 by screws or other means as desired. Mounted on the body 1 is a 25 handle 3 which may be wood, metal or other desired material, and which may be of any desired shape in cross section, that shown in the drawing being round. In mounting the handle 3 in place, two holes are formed in the body 1, said holes being preferably an equal 30 distance in front and rear of the strap 2. The ends of the handle 3 are inserted into these holes as shown in Figure 2, and then a wedge 4 forced into the split 5 whereby the 35 respective ends are wedged or clamped tightly to body 1.

40 In Figure 3, a modified form of securing means is provided. In this form of the invention, the ends of the handle 3 are split a short distance, and a wedge 5' forced therein so that the ends of the handle will press tightly against the block 6. This block is provided with a hole for receiving the ends of the handle, and then the block is secured 45 to body 1 by suitable fastening means, as for instance, screws 7. It will be understood that there is a block 6 for each end of the handle 3, and that these blocks are comparatively short, as for instance, only a few inches long 50 and two or three inches wide.

In forming the handle 3, the same may be a half circle, or may extend upwardly a short distance at right angles to the body 1 and then formed into a half circle as shown in Figure 1. The arc-shaped formation of the 55 handle is of considerable advantage, and particularly is positioned so as to straddle the strap 2. When a tall person is using the ski, the hands may grasp the center of the upper part of the handle, but if the person is comparatively short, the hands of the person will grasp the handle 3 half way down or at any desired point along the handle, thus permitting different size persons to grasp the handle 60 at the most convenient place. Under some 65 circumstances, a person using the skis may wish to grasp the handle in front of the strap 2 and this may be done as readily as grasping the handle at the rear. The handle will act not only as means for supporting a person 70 steadily on the ski, but as means for steering the ski or raising the forward end above some obstacle. The handle 3 is also made with a comparatively deep loop whereby the same 75 may be passed over the head and caused to rest on one of the shoulders when carrying the ski. In this way the handle acts as a sling, and when in use, acts as a handle which 80 may be used or may be ignored as preferred.

What I claim is:

1. A ski provided with a body, a foot clamping strap connected with said body intermediate the ends, and a substantially arc-shaped handle carried by said body but looped over said strap, said handle being of 85 a height to be grasped by the hands of the person using the ski.

2. A ski provided with a body, a foot strap and a looped handle, said looped handle having front and rear sections extending at right 90 angles to the body, and a substantially arc-shaped section connecting said right angle sections, said arc-shaped section being spaced above said body sufficiently to permit a person using the ski to grasp the handle without 95 stooping.

3. A ski, comprising a body, a foot strap and a substantially arc-shaped handle positioned with its ends substantially an equal 100 distance from the front and rear respectively

of said strap, the top of said arc-shaped handle being spaced above said body sufficiently to permit a person using the ski to grasp the handle without stooping.

5 4. A ski formed with a body, a substantially arc-shaped handle projecting into said body, and a wedge in each end of said handle

for pinching the ends of the handle against the body.

Signed at New York, in the county of New ¹⁰ York and State of New York, this 9th day of December, A. D. 1927.

ANDREW E. MARTINSON.
